UNITED STATES PATENT OFFICE

HOWARD J. CLAXTON, OF CHICAGO, ILLINOIS

VALVE-GEAR CONTROL

Application filed June 25, 1927. Serial No. 201,510.

This invention relates to certain novel improvements in valve gear controls.

It has been found in the railroad art that the valve gear of a locomotive tends to creep after having once been set and thus the speed of a locomotive varies. It is therefore the salient object of my invention to provide a device which will prevent creeping of the valve gear of a locomotive.

A further object of the invention is to provide a construction adapted to be used on the valve gear of a locomotive so as to afford expeditious movement thereof.

A still further object of the invention is to provide such a device which will be simple in construction and operation and economical to manufacture.

Other objects will appear hereinafter.

The invention consists in the novel combination and arrangement of parts to be hereininafter described and claimed.

The invention will be best understood by reference to the accompanying drawings, showing the preferred form of construction and in which:

Fig. 1 is a side elevational view of a locomotive embodying a preferred form of my invention;

Fig. 2 is an enlarged detail view of lever connections employed in my device; and

Fig. 3 is a longitudinal sectional view of a portion of the apparatus.

Referring to the drawings wherein the preferred embodiment of my invention is illustrated, it may be seen that I show a locomotive 10 embodying drive wheels 11 and 12 which are actuated by the usual cross-head construction that is operated by pistons caused to reciprocate in the usual cylinders 13. As is well understood in the art, a suitable valve gear is provided for directing the steam into the cylinders and inasmuch as the specific form of valve gear forms no part of my invention, no detailed description thereof will be given herein.

A bell crank 14 is mounted on the side of the locomotive which is adapted to connect the valve gear and allied appurtenances to the usual control lever. My invention is particularly adapted to be disposed between the usual

control lever 15 and the usual bell crank 14. In place of the link which ordinarily connects the lever 15 to the bell crank 14, I provide a link 16 that is pivotally attached to the bell crank 14 as at 17.

On the side of the locomotive, preferably in the location best depicted in Fig. 1, I provide a slide bar construction 18 on which a cross-head 19 is adapted to reciprocate. The link 16 is suitably connected to the cross-head 19 as at 20 and therefore movement of the cross-head 19 will cause actuation of the valve gear in a manner similar to the usual link which ordinarily connects the bell crank 14 to the control lever 15. It is to be understood that as the position of the lever 15 is varied, the speed of operation and the direction of operation of the locomotive may be controlled either in devices of the prior art or in the present device.

Mounted on the side of the locomotive in juxtaposition to the cross-head 19 is a cylinder 21 embodying a portion 22 which is of less cross-sectional area than the portion 23 thereof. Mounted for reciprocation along the walls of the portion 22 is a piston 24 which embodies a head 25 to which the connecting rod 26 is suitably secured. The connecting rod 26 protrudes through an opening in the cylinder head 27. Disposed around the connecting rod 26 at said opening is a suitable packing gland 28. The connecting rod 26 is adapted to be attached to the cross-head 19 for a purpose to be brought forth hereinafter.

On the end of the piston 24 opposite the head 25 an enlarged portion 29 is provided that is adapted to ride in the walls of the portion 23 of the cylinder 21. Mounted within the cylinder 21 at the end opposite the head 27 is a sleeve 30 which has a flange 31 thereon that is adapted to be secured to the cylinder 21 by suitable means such as the bolts 32. The sleeve 30 is adapted to protrude into the interior of the piston 24 in such a way that said piston shall be slidable thereon. The inner end of the sleeve 30 embodies a head 33 having a recess 34 therein into which the nut 35 is adapted to fit when the piston 24 is moved so as to be adjacent to the head 33 of the sleeve 30. The nut 35 is adapted

to engage suitable screw threads on the inner end of the connecting rod 26 in order to secure said rod to the piston 24. Piston rings such as 36 are provided on the piston 24 adjacent to the head 25 thereof. Piston rings 37 are provided in the portion 29 of the said piston. Piston rings 38 are provided on the sleeve 30 adjacent to the head 33 thereof, the utility of the piston rings 36, 37 and 38 being 10 well understood in the art.

By referring to Fig. 2, it may be seen that the control lever 15 is pivotally mounted at 39 and a segment 40 is provided adjacent said lever, said segment having notches 41 formed therein that are adapted to be engaged by the retaining pawl 42 adapted to be operated by the suitable latch structure generally indicated at 43. It is apparent that the lever 15 may be rocked about its 20 pivot point 39 and that the retaining pawl 42 may be caused to engage the notches 41 so as to hold said lever 15 in any desired position. The position indicated in Fig. 2 is a neutral position. The movement of said lever in one 25 direction will cause the locomotive to move forward and movement of the said lever in the opposite direction will cause said locomotive to move rearward. Provided adjacent to the cylinder 21 is a lever 44 that is pivotally 30 mounted as at 45. A link 46 is pivotally secured to the lower end of the lever 15 and to the upper end of the lever 44. A lever 47 is provided and a link 48 is pivotally attached to said lever 47 as at 49, said link 48 also being attached to the lower end of the lever 44. The valve rod 50, which will be described in detail hereinafter, is pivotally attached to the upper end of the lever 47. A downwardly protruding boss 41 is provided on the cross-head 19 and a link 52 is pivotally secured thereto, said link also being pivotally secured to the lower end of the lever 47.

As the lever 15 is moved after withdrawing the retaining pawl 42 from one of the notches 41, the movement thereof is transmitted to the lever 44 by the link 46 and said lever 44 is caused to rock about its pivot point 45 dependent upon the direction of the movement of the lever 15. A movement of the lever 44 is transmitted to the lever 47 by the link 48 and therefore inasmuch as the cross-head 19 will be held in a fixed position in a manner to be described, the lever 47 will rock about the pivotal connection between said lever and the link 52 and thus the valve rod 50 will be moved for a purpose to be brought forth hereinafter.

On the upper side of the cylinder 21, a valve housing 53 is provided and the valve rod 50 protrudes through an opening 54 provided in one of the walls of said valve housing. Mounted on the upper side of the cylinder 21 within the valve housing 53 is a block 55 having a plurality of ports therein, the 60 utility of which will be presently described.

Mounted for sliding movement on the block 55 is a slide valve 56. Leaf springs 57 are provided on the upper side thereof that is adapted to engage the inner surface of the upper side of the valve housing 53 in order to hold the slide valve 56 in engagement with the block 55. The valve rod 50 is secured to the slide valve 56 in order that said slide valve shall be moved thereby. Suitable ports are provided in the slide valve 56 which are 70 adapted to interconnect the ports with the block 55 in a manner to be described hereinafter.

As stated, the valve rod 50 is adapted to move the slide valve 56 and further, as has been stated, said slide valve embodies a plurality of ports which are adapted to interconnect the ports in the block 55. Further, when the control lever is moved, it is of course necessary to move the bell crank 14 in order to alter the usual valve gear. This is done by actuating piston 24 which in turn moves the cross-head 19 and movement of the cross-head 19 is transmitted to the bell crank 14 by the link 16. Movement of the piston 24 is accomplished in the following manner. An opening 58' is provided in the walls of the cylinder 21 adjacent the head 27 thereof and a conduit 58 extends through the opening 58' so as to be in communication with the portion A of the cylinder 21. The conduit 58 terminates in a port 59 in the block 55. A port 60 is provided in the slide valve 56 and is adapted to register with the port 59 when the valve rod 50 moves said slide valve 56. A conduit 61 is adapted to be in communication with the interior of the valve housing 53 and said conduit 61 is also connected to the usual compressed air system provided on the locomotive. Therefore when the port 60 registers with the port 59, air will flow from the air system through the conduit 61 to the interior of the valve housing 53, through the port 60, port 59, conduit 58, into the portion A of the cylinder 21. A port 62 is provided in the slide valve 56 and at the time the port 60 registers with the port 59, the port 62 will register with the port 63 provided in the block 55. The conduit 64 connects the portion B of the cylinder 21 with the port 63. A port 65 is provided in the block 55 which is adapted to be in communication with the atmosphere and therefore when air is forced into the portion A of the cylinder 21, the air in the portion B will travel through the conduit 64 and port 63, port 62 and thence out through port 65, and thus relieve pressure in back of the piston 24 so that the pressure in front of said piston will be able to move said piston toward the head 33 of the sleeve 30.

As stated, a liquid seal is provided which is adapted to be disposed in equal amounts on opposite sides of the piston 24 in order to prevent creeping thereof. The portion C 130

of the cylinder 21 is adapted to be filled with a suitable liquid such as oil and a conduit 66 which extends through the head 33 of the sleeve 30 is adapted to be in communication with the portion C of the cylinder 21. The conduit 66 is connected to the port 67 provided in the block 55. A port 68 is provided in the block 55 and a conduit 69 connects this port with the portion D of the cylinder 21. It is apparent that the portions C and D in the cylinder 21 are disposed on opposite sides of the piston 24. A suitably formed port 70 is provided in the slide valve 56 which is adapted to inter-connect the ports 67 and 68 when the ports 59 and 60 are brought into register and therefore as the piston 24 is moved, oil will be transferred from the portion C through the conduit 66, port 67, port 70, port 68, and conduit 69 to the portion D of said cylinder.

It is apparent that as soon as the valve rod 50 is moved in the manner heretofore described, if said valve rod moves rearwardly the port 59 registers with the port 60 and air will be forced into the portion A of the cylinder 21 which will move the piston 24. As the piston 24 moves, the air in the portion B will escape in the heretofore described manner through the port 65 and the liquid in the portions C and D will interchange in the manner described. As the piston 24 moves, the movement thereof is transmitted to the connecting rod 26 to the cross-head 19. As said cross-head moves, the movement thereof will be transmitted to the valve gear in the heretofore described manner. Movement of the cross-head 19 will also be transmitted to the lever 47 through the lever 52 and inasmuch as the link 48 will be fixedly held at this time, the lever 47 will rock about the pivotal connection 49 between said link and said lever and thus the valve rod 50 will be moved to the position illustrated in Fig. 3, which will close communication between the various ports and thus the movement of the piston 24 will be interrupted and said piston will be fixedly held in position, inasmuch as there is an equal fluid pressure on both sides thereof.

When the valve rod 50 is caused to move in a direction opposite from that described, a portion of the slide valve 56 which is shown as closing communication to the port 63, will be moved to a point between the port 63 and the port 65 and therefore air from the conduit 61 will flow through the conduit 64 into the portion B of the cylinder 21 which will move the piston 24 away from the head 33 of the sleeve 30. At this same time, the port 62 will register with the port 59 and will permit the air in the portion A of the cylinder 21 to flow through the conduit 58, port 59, port 62, and out through the port 65 so as to be discharged. It is apparent that the port 70 is arranged so it will inter-connect

ports 67 and 68 regardless of which direction the slide valve 56 is moved.

The portions A and B of the cylinder 21 have suitable drain cocks 71 provided therein in order that water and other foreign matter carried into these portions by the air may be discharged therefrom. A drain cock such as 72 is provided in the portion D in order that oil may be drained from the system. Suitable filling plugs may be associated with the chambers C and D whereby the oil supply may be introduced or replenished.

It is apparent from the foregoing that I have provided an arrangement whereby the valve gear of the locomotive may be expeditiously moved and one in which said valve gear will be fixedly held in position after it has been moved to a predetermined point.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention what I claim as new and desire to protect by Letters Patent is:

1. In a device of the class described, a substantially tubular member including an enlarged portion at one end thereof whereby an enlarged bore and a smaller bore are defined therein and having a shoulder at the junction of said bores, a cylindrical member mounted in said enlarged bore and having the closed inner end thereof disposed in alignment with said shoulder, a piston having a skirt portion disposed over said cylindrical member and extended into said smaller bore, a head adapted to close the outer end of said smaller bore whereby a chamber will be defined in said smaller bore between said head and the inner end of said piston, said piston providing a second chamber interiorly thereof in front of the closed end of said cylindrical member, said cylindrical member having a foot portion closing the outer end of said enlarged bore, said piston skirt having a foot portion adapted to define a chamber between said shoulder and said foot portion and adapted to define another chamber between the foot portion of said cylindrical member and said foot portion on said skirt, means for interconnecting the second named chamber and the third named chamber, means for interconnecting the first named chamber and the fourth named chamber, and valve means disposed in said connecting means adapted to be arranged such that communication between said chambers through said connecting means may be controlled.

2. In a device of the class described, a

substantially tubular member including an enlarged portion at one end thereof whereby an enlarged bore and a smaller bore are defined therein and having a shoulder at the juncture of said bores, a cylindrical member 5 mounted in said enlarged bore and having the closed inner end thereof disposed in alignment with said shoulder, a piston having a skirt portion disposed over said cylindrical member and extended into said smaller bore, 10 a head adapted to close the outer end of said smaller bore whereby a chamber will be defined in said smaller bore between said head and the inner end of said piston, said piston providing a second chamber interiorly 15 thereof in front of the closed end of said cylindrical member, said cylindrical member having a foot portion closing the outer end of said enlarged bore, said piston skirt having a foot portion adapted to define a chamber 20 between said shoulder and said foot portion and adapted to define another chamber between the foot portion of said cylindrical member and said foot portion on said skirt, a valve construction having ports formed 25 therein and having a slidable member adapted to control communication between said ports, means for connecting said ports and said chambers whereby said valve member may be moved to permit passage of a motive 30 medium into said first named chamber while said motive medium is permitted to escape to the atmosphere from said fourth named chamber whereby a liquid may be permitted to pass from said second named chamber into 35 said third named chamber, said valve member being adapted to be moved to permit said motive medium and said liquid to move in the opposite directions whereby said piston may be moved or held against movement.

40 In testimony whereof I affix my signature.

HOWARD J. CLAXTON.
